UNITED STATES PATENT OFFICE.

JOHN MUIR, OF BRANTFORD, CANADA, ASSIGNOR TO THE STOVER MANUFACTURING COMPANY, OF FREEPORT, ILLINOIS.

WINDMILL.

SPECIFICATION forming part of Letters Patent No. 628,412, dated July 4, 1899.

Application filed November 2, 1898. Serial No. 695,267. (No model.)

To all whom it may concern:

Be it known that I, JOHN MUIR, a citizen of the Dominion of Canada, residing at Brantford, in the Province of Ontario, Dominion of Canada, have invented certain new and useful Improvements in Windmills; and I do hereby declare the following to be a full, clear, and exact description of the invention, such as will enable others skilled in the art to which it appertains to make and use the same.

The invention relates particularly to such windmills as drive a pump-rod or other reciprocating part. In mills of this kind the wind-wheel shaft is usually provided with a crank and pitman, and as this construction involves great strain and wear in the windmill-head, which is not easily reached nor readily repaired when reached, owing to construction and for other reasons deemed necessary, many devices have been used to lessen the evils suggested.

The object of this invention is to eliminate the evils completely, and this object is attained by placing the crank and pitman in the tower below and providing means whereby they may be driven by the latter without the usual lateral strains.

In the accompanying drawings, Figure 1 shows the head and the upper portion of the tower of a windmill provided with my devices. Fig. 2 is a detail view showing parts as seen when looking in the direction of the arrow of Fig. 1.

In the figures, A represents a steel tower having a cap B, supporting a turn-table B'. Far below this turn-table and within the tower is a second and parallel turn-table G, consisting of a flanged and braced horizontal ring fitting within and upon a ring H or equivalent bearings attached to the contiguous posts of the tower. The two turn-tables are connected by members F F', extending downward from the head proper, C, and forming with the turn-tables one rigid structure, which supports above the tower the usual wind-wheel spider and shaft D E and vane D'. Below the lower table is a shaft K, parallel to the wind-wheel shaft and supported in a long bearing in the lower portion of the structure just described. Upon the two shafts, respectively, are mounted two pulleys or sprocket-wheels I J in the same plane and nearly in the vertical axis of the mill. A belt

or chain L connects the two pulleys, and preferably the pulleys lie in a plane perpendicular to the plane of the members F F' and midway between them. The lower pulley bears a wrist-pin N, and to this is attached a pitman to be connected with a pump-rod or the like. This greatly-elongated head supported by the two widely-separated turn-tables holds the mill with steadiness and security, and the thrust of the pitman is borne by parts located where there is ample space for strong construction, where the parts are supported on all sides by the tower-posts, and where they are readily accessible without dangerous exposure upon the top of a tower and in a plane swept by shifting wheel and vane.

It is obvious that the lower pulley may be above the ring and that its distance from the head may be such as is deemed desirable, and it is equally plain that the construction set forth may be varied in other respects without passing the proper limits of my invention.

What I claim is—

1. The combination with the tower and the turn-table upon its top, of a turn-table mounted within the tower at some distance below its top, the head members extending down through both turn-tables and rigidly connecting them, the wind-wheel shaft mounted above the tower, the parallel shaft supported by said members near the lower turn-table, pulleys fixed upon the shafts, respectively, in the same plane, a belt connecting the pulleys, and a pitman carried by the lower pulley.

2. The combination with the tower and its cap, of the ring within the tower and fixed to its posts at some distance below its top, the turn-table above the cap, the turn-table supported in said ring, the head having members forming with the two turn-tables a rigid rotary structure, a wind-wheel shaft in the head above the tower, a parallel shaft mounted in said structure near the lower turn-table, pulleys in the same plane upon the two shafts, respectively, a belt connecting the pulleys and a pitman carried by the lower pulley.

In testimony whereof I affix my signature in presence of two witnesses.

JOHN MUIR.
